HARRY S. DICKINSON, M.D.

UNITED STATES PATENT OFFICE.

BERT C. BERRY, OF CALGARY, ALBERTA, CANADA, AND HARRY S. DICKINSON, OF MOLINE, ILLINOIS, ASSIGNEES, BY DIRECT AND MESNE ASSIGNMENTS, TO PEERLESS SHOCK LOADER COMPANY, OF WILMINGTON, DELAWARE, A CORPORATION OF DELAWARE.

SHOCK LOADER.

Application filed July 28, 1923. Serial No. 654,407.

This invention relates to loaders for shocks or sheaves of grain or like material, and has for its object to eliminate the use of gears, sprockets, or like transmission elements ordinarily employed for the purpose of rotating the elevating cylinder, and to provide in lieu thereof a contacting wheel-like element which, when in ground contact, will directly rotate the cylinder, and, when lifted, will remain idle, so that the machine may be readily transported across the field or on a road, as occasion may require.

A further object of the invention is to so construct the supporting frame for the implement as a whole that the ground contacting element and associated mechanisms may be easily raised and lowered as desired by power lifting means adapted to be actuated by the draft of the implement.

A further object of the invention is to provide means for adjusting or regulating the space intermediate the throat of the gathering teeth and cylinder teeth, and to provide yieldable elements at this point adapted to recede under excessive pressure to prevent choking of the machine.

A further object of the invention is to provide supplemental elevating means associated with the elevating cylinder for lifting the material to a high level in order to reduce the length of the inclined transverse conveyor which ultimately deposits the material on the accompanying wagon.

Further objects will appear from a detailed description of the invention which consists in the features of construction and combinations of parts hereinafter described and claimed.

In the drawings:

Figure 1 is a side elevation of the machine showing the ground power wheel in elevated position;

Fig. 2 is a plan view of the same;

Fig. 3 is a detail showing the brake mechanism for actuating the power lift;

Fig. 4 is a skeletonized view showing a modified form of supplemental elevator; and Fig. 5 is a detail of the rim of the wheel shown in Fig. 4.

The machine as a whole is mounted upon a pair of ground wheels 10 and a forward steering wheel 11, which latter is journaled within a caster bracket 12 carrying a pintle 13 to

which a tongue 14 is preferably secured. The ground wheels are suitably spaced on opposite sides of the machine, and are journaled upon the outturned stub ends 15 of an arched axle 16, the upper transverse portion of which is journaled within a pair of journal brackets 17 secured to the side rails 18 of a main frame, which side rails are cross connected at their rear ends by means of a rear cross rail 19. The forward end of the main frame supports a transverse inclined endless conveyor 20 of the usual character.

The elevated central portion of the arched axle serves as an elongated mounting for a drum 21 provided with a plurality of rows of teeth or tines 22 which are forwardly curved at their outer ends 23 and are braced at their forward sides by the provision of diagonally extending brace bars 24 which extend in obtuse relation to the adjacent surface of the cylinder, so that as the teeth sweep around to discharging position, the shocks or bundles will not be cramped or crowded into acute angular relation with respect to a conveyor deck composed of a series of endless belts 25 which surround the drum intermediate the teeth or tines and extend forwardly and upwardly to a belt drum 26 suitably supported in proximate relation to the transverse conveyor 20. The upper turns of the belts composing the elevator deck extend upwardly at a slight incline and serve to provide a moving surface for stripping the material from the teeth or tines 22 and carry it upwardly to the point of discharge onto the transverse elevator. The arrangement is one which elevates the material to a sufficient point to obviate the necessity for providing an excessively long transverse elevator or for providing lateral extensions thereof, as is customary in implements of this character.

The belt drum 26 is mounted upon a transversely extending shaft 27 which carries the pinion 28 which imparts rotation to gearing 29 for rotating the transverse conveyor shaft 30, so that special gear sprockets or the like are not required. The cylinder 21 serves as a hub for a power wheel 31 connected to the cylinder by spokes 32, which power wheel occupies a position adjacent to one end of the cylinder and is of a diameter to be lifted out of contact with the ground when the arched axle is moved into a substantially vertical

plane, as indicated in Fig. 1. When, however, the lower depending legs of the arched axle are moved forwardly into oblique relation with respect to the main frame, it will allow the main frame to descend sufficiently to bring the ground wheel into ground engaging position, thereby causing the implement to move forward on the five ground wheel supports instead of four and impart rotation to the elevating cylinder and parts associated therewith.

The elevating cylinder co-operates with a set of gathering teeth 33 which near their upper ends are provided with guide brackets 34 which embrace the transversely extending cross connection 19 and permit the teeth to be moved vertically with respect thereto. Each tooth on its forward or acting face has secured thereto an adjusting tine 35 preferably of curved formation, as shown, which tine is fixedly secured at its lower end to the associated tooth and is spring connected at its upper end through the medium of a rearwardly extending adjusting bolt 36 fixed to the tine and slidably entered through the tooth, which bolt carries an interposed spring 37, and the bolt is adapted to be drawn back by means of a nut 38, so that the normal position of the tine can be adjusted against spring tension to the desired degree. This arrangement provides a spring surface of contact for material so that in case an excessive amount of material is carried up to the point indicated, the tines will yield sufficiently to prevent choking of the machine.

The gathering teeth near their lower ends are supported by a U-shaped draft frame comprising side arms 39 and a rear cross connection 40, to which cross connection the several teeth are secured by links 41, which arrangement permits the teeth to individually accommodate themselves to ground inequalities which may be encountered. The vertical elevation of the entire series of teeth may be regulated by raising or lowering the draft frame, the arms of which, on opposite sides of the machine, are pivoted at the points 42 to the adjacent side rails of the main frame. In order to provide for the raising and lowering of the draft frame, draw rods 43 are employed, which rods on each side of the machine, extend forwardly and connect with the upper arms of levers 44, which levers are rigidly mounted upon a transversely extending rock shaft 45, so that the parts will operate in unison on both sides of the machine.

The lower arm of each lever 44 is connected with the downwardly extending portion of the arched axle by means of a draw rod 46 adapted to exert a pull on the lower ends of the arched axle so that as the latter is thrown out of vertical relation to the draft frame (as shown in Fig. 1), the ground power wheel 31 will drop into ground engaging position, and the rear upper ends of the draft frame

will fall back rearwardly and downwardly with respect to the ground wheels 10 with a consequent lowering of the draft frame and the gathering teeth carried thereby, which latter will thus come into ground engaging position. Motions are imparted to one of the levers 44 through the medium of a draw rod 47, the forward end of which is connected to the lower end of a hand lever 48 pivoted in suitable proximity to the driver's seat.

In order to facilitate the raising of the draft frame, springs 49 on opposite sides are provided which serve to counterbalance the weight of the draft frame and the gathering teeth. In order to utilize the draft of the machine for the purpose of lifting the rear end thereof to elevate the ground power wheel out of ground engaging position, the following means are provided: One or both of the ground wheels 10 is provided with a brake drum 50 and brake band 51 one end of which is directly secured to the adjacent portion of the arched axle 16, and the other end of which is secured to the bell crank lever 52, the upper end of which is engaged by a draw rod 53 which in turn connects with a lower end of a lever 54, the upper end of which connects with a forward draw rod 55 which in turn is pivoted to the lower end of a brake hand lever 56 closely adjacent to the hand lever 48, all as indicated in Fig. 3. A notched segment 57 is provided in proximate relation to the hand lever 48, so that the latter may be held in adjusted position.

In operation, the machine, adjusted as in Fig. 1, is drawn to the field and when the point is reached to begin operations, the driver thrusts the hand lever forwardly, which, through the connection shown, draws forward the lower legs of the arched axle 10 into oblique relation with the frame, thereby allowing the rear end of the frame to descend until the ground power wheel comes into ground engagement. Simultaneously through the connection shown, the gathering teeth are lowered into ground engaging position, after which the continued advance of the machine will cause the elevating cylinder to rotate and the inclined cross conveyor to travel toward the discharging side of the machine.

As a shock of grain is encountered, the teeth of the elevating cylinder will sweep down over the head of the shock and topple the head backwardly, and at the same time the gathering teeth will pass under the base of the shock so that the same will be carried up head-first and thereafter it is deposited head-first upon the transverse conveyor which in turn will carry it upwardly and laterally in position to be discharged into the wagon which travels alongside the loader without material disarrangement of the sheaves composing the shock. The operation above outlined will continue until completed, after

which, in order to lift the rear end of the machine out of ground engaging position, the operator will unlatch the main hand lever and simultaneously draw back on the brake lever, which movement of the brake lever will set the brakes on the supporting ground wheels, so that they will cease to rotate, and thereafter, as the machine advances, the non-rotating wheels will be drawn back in position to bring the arched frame into substantially vertical relation, thereby affording the necessary lift to disengage the ground power wheel. After this movement is effected, the brakes are released, and the main hand lever latched to retain the parts in elevated position. The lifting movements effected in the manner indicated will, also through the connection shown, serve to exert a forward pull on the draw rod 43 which elevates the rear end of the draft frame which supports the gathering teeth so that the latter will automatically assume a sufficiently elevated position to clear the ground as the machine is driven from the field or on a road.

The employment of the elevating belts affords a high point of discharge to the cross conveyor, so that the length of the latter may be reduced proportionately, and at the same time the elevating belts afford a moving stripper for the cylinder teeth and a means for the transmission of power to the cross conveyor. In lieu of the elevating belts, the supplemental elevator shown in Fig. 4 may be employed. This elevator comprises a drum 58 which serves as a mounting for a series of radially arranged rotating teeth or tines 59 which rotate in concordant relation to the teeth of the main elevator drum and sweep above the surface of a fixed inclined stripper deck 60 suitably slotted to permit of the passage of the teeth 22. Rotation is imparted to the supplemental rotating elevator through the medium of a butterfly wheel 61 which is secured at one end to the drum 58 in suitable relation to have its wings engaged by a plurality of laterally projecting pins 62 carried by the rim of the ground wheel 31, the arrangement being such that as the ground wheel rotates in the direction indicated, a rotating motion will be imparted to the supplemental elevator, the teeth of which will sweep forwardly and carry the shocks or bundles along the stripper deck and onto the cross conveyor 20.

In using the supplemental elevating mechanism of Fig. 4, the belts 25 are replaced by the fixed stripper deck 60, although a single one of the belts may be retained for the transmission of power to the cross conveyor or other adequate power transmission means may be utilized. Save in respect to the special features indicated, the mechanism of Fig. 4 operates in the same manner as has already been described.

The machine of the present invention is

one which is extremely simple in construction and in mode of operation as compared with loaders which utilize gears, clutches, and like power transmission elements, in that the principal elevating operation is performed directly by ground engagement of the power wheel, and this arrangement permits of the employment of relatively small carrying ground wheels and at the same time locates the axis of the elevating cylinder at a high point which is desirable in order to secure the necessary elevation of the shocks or other material.

The method of stripping the shock or other material from the teeth of the rotating cylinder either by moving belts or by a rotating toothed supplemental drum is distinctly superior to the employment of fixed elements for stripping purposes, not only in that it ensures a more positive stripping action but also because the forward and upward advance of the material is positively continued by the engagement of moving elements at these points, and this ensures a high delivery of the material to the cross conveyor.

We claim:

1. In a loader, the combination of gathering teeth, an elevator, a member fixed to the elevator and adapted to engage the ground to actuate the elevator, and means for lifting said ground engaging means out of ground contact, substantially as described.

2. In a loader, the combination of gathering teeth, a rotatable elevator, supporting wheels for supporting the rotatable elevator, a power wheel connected to the elevator, and means for lifting the elevator and its associated ground wheel out of ground contact, substantially as described.

3. In a loader, the combination of gathering teeth, a rotatable elevator, supporting wheels for supporting the rotatable elevator, a power wheel connected to the elevator, means for lifting the elevator and its associated ground wheel out of ground contact, said means comprising a pivotally arched axle upon which the supporting wheels are journaled, and means for varying the angle of said arched axle, substantially as described.

4. In a loader, the combination of a frame, gathering teeth carried by the frame, a rotatable elevator in co-operative relation to said gathering teeth, a power wheel connected to said elevator, an arched axle having its elevated portion pivoted to said frame, supporting wheels journaled at the lower ends of said arched axle, and means for adjusting the arched axle to bring the power wheel into and out of ground contact, substantially as described.

5. In a loader, the combination of a frame, gathering teeth carried by the frame, a rotatable elevator in co-operative relation to said gathering teeth, a power wheel connect-

ed to said elevator, an arched axle having its elevated portion pivoted to said frame, supporting wheels journaled at the lower ends of said arched axle, and a power lift for 5 swinging said arched axle to disengage the power wheel from ground contact, substantially as described.

6. In a loader, the combination of a frame, gathering teeth carried by the frame, a rotatable elevator in co-operative relation to said gathering teeth, a power wheel connected to said elevator, an arched axle having its elevated portion pivoted to said frame supporting wheels journaled at the lower ends 10 of said arched axle, means for adjusting the arched axle to bring the power wheel into and out of ground contact, and a power lift 15 for swinging said arched axle to disengage the power wheel from ground contact, said 20 power lift including a brake for momentarily stopping the rotation of a supporting wheel to cause a rearward swinging movement of the arched axle, substantially as described.

25 7. In a loader, the combination of a frame, a rotatable elevator journaled to the frame, gathering teeth in proximate relation to the teeth of the elevator, a power wheel carried by the elevator rotatable therewith, an arched 30 axle having its upper portion pivoted to the frame, supporting wheels journaled on the lower ends of the arched axle, adjusting means for swinging the arched axle forwardly to lower the power wheel into ground 35 engaging position, and a brake for stopping rotation of one of the supporting wheels to cause a rearward swinging of the arched axle towards vertical position to effect a lifting of the power wheel substantially as described.

40 8. In a loader, the combination of a frame, a rotatable elevator journaled to the frame, gathering teeth in proximate relation to the teeth of the elevator, a power wheel carried by the elevator rotatable therewith, an arched 45 axle having its upper portion pivoted to the frame, supporting wheels journaled on the lower ends of the arched axle, adjusting

means for swinging the arched axle forwardly to lower the power wheel into ground engaging position, and a brake for stopping rotation of one of the supporting wheels to cause a rearward swing of the arched axle towards vertical position to effect a lifting of the power wheel and gathering teeth, substantially as described.

50 9. In a loader, the combination of a frame, an elevator carried by the frame, gathering teeth carried by the frame, a ground engaging member for imparting power to the elevator, supporting wheels, and mountings for the supporting wheels carried by the frame and adjustable with respect thereto to vary the vertical distance between the supporting wheels and the frame to the degree required to move the ground engaging power member into and out of ground contact, substantially 55 as described.

10. In a loader, the combination of a frame, a rotatable elevator carried by the frame, a ground engaging power wheel operatively connected to the elevator, gathering teeth in proximate relation to the elevator, supporting wheels, and mountings for the supporting wheels carried by the frame and adjustable with respect thereto to vary the vertical distance between the ground wheels and the frame to the degree required to move the power wheel into and out of ground engaging 70 position, substantially as described.

75 11. In a loader, the combination of a frame, an elevator mounted on the frame, supporting wheels for the frame, a vertically adjustable ground engaging device for furnishing power to the elevator, means for effecting vertical adjustment of the ground engaging device, gathering teeth carried by the frame in proximate relation to the elevator, means for vertically adjusting the gathering teeth, and co-operating connections for simultaneously actuating the ground engaging lifting 80 means and the means for lifting the gathering teeth, substantially as described.
